US00D842058S

(12) **United States Design Patent** (10) **Patent No.:** **US D842,058 S**
(45) **Date of Patent:** **** Mar. 5, 2019**

(54) **LOCKING COVER OF TORQUE WRENCH**

* cited by examiner

(71) Applicant: **TORQUE-TECH PRECISION CO., LTD.**, Taichung (TW)

Primary Examiner — Randall H Gholson

(72) Inventor: **Tien-Lung Lin**, Taichung (TW)

(74) *Attorney, Agent, or Firm* — Ming Chow; Sinorica, LLC

(73) Assignee: **TORQUE-TECH PRECISION CO., LTD.**, Taichung (TW)

(57) **CLAIM**

(***) Term: **15 Years**

I claim the ornamental design for a locking cover of torque wrench, as shown and described.

(21) Appl. No.: **29/637,785**

DESCRIPTION

(22) Filed: **Feb. 22, 2018**

FIG. 1 is a front perspective view of a locking cover of torque wrench showing my new design;

(51) **LOC (11) Cl. 08-05**

FIG. 2 is a front elevational view thereof;

(52) **U.S. Cl.**

FIG. 3 is a rear elevational view thereof;

USPC **D8/24**

FIG. 4 is a left side elevational view thereof;

(58) **Field of Classification Search**

FIG. 5 is a right side elevational view thereof;

USPC D8/21-29; 81/60, 177.1, 177.85, 121.1,

FIG. 6 is a top plan view thereof;

81/124.3, 165-170, 110.1, 176.2, 124.6,

FIG. 7 is a bottom plan view thereof;

81/176.1, 176.15, 177.2; 16/110.1;

FIG. 8 is another perspective view thereof;

D15/144.1; 219/75, 227, 229, 121.16,

FIG. 9 is a front end view of the locking cover of torque wrench in accordance with my design, shown in its environment thereof; and,

219/121.18

FIG. 10 is another front end view of the locking cover of torque wrench in accordance with my design, shown in its environment thereof.

CPC B25B 13/00

The broken lines are for the purpose of illustrating environmental structure and form no part of the claimed design.
